UNITED STATES PATENT OFFICE.

FRANZ CECKA, OF CHEMNITZ, GERMANY, ASSIGNOR TO FIRM OF SCHUBERT & SALZER
MASCHINENFABRIK, AKTIENGESELLSCHAFT, OF CHEMNITZ, GERMANY.

HOSIERY-FRAME.

1,217,410.

Specification of Letters Patent. Patented Feb. 27, 1917.

Application filed July 22, 1914. Serial No. 852,417.

To all whom it may concern:

Be it known that I, FRANZ CECKA, a citizen of the German Empire, residing at Chemnitz, in the Kingdom of Saxony, Germany, have invented certain new and useful Improvements in Hosiery-Frames; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to improvements in hosiery frames, and more particularly in the mechanism for reducing and increasing the inward stroke of the thread guide.

20 When making reinforced portions in knitted goods on flat hosiery frames the inward stroke of the thread guide is limited by means of fixed stops which correspond to the desired breadth of the reinforced portion. By means of such a mechanism only reinforced portions can be made which have straight border lines, while it is not possible to make fancy reinforced portions.

25 The object of the improvements is to provide a mechanism by means of which fancy reinforced portions can be made. With this object in view my invention consists in providing mechanism for limiting the inward stroke of the thread guide which can be regulated automatically while the machine is in operation.

30 For the purpose of explaining the invention one example embodying the same has been shown in the accompanying drawings, in which the same letters of reference have been used in all the views to indicate corresponding parts. In said drawings—

35 Figure 1, is a diagrammatical view showing the heel portion of a stocking made with a fancy reinforced portion,

40 Fig. 2, is a front view of the mechanism for making fancy reinforced portions in knitted goods,

45 Figs. 3 to 5, are diagrammatical views showing the stops for limiting the inward stroke of the thread guide in different positions.

50 In addition to the usual thread guides provided for knitting the non-reinforced parts of the work thread guides 3 and 4 are

provided, which coöperate with the said usual thread guides in knitting reinforced portions, as is known in the art. For clearness sake only the thread guides 3 and 4 have been shown, which are secured in the usual way to thread guide bars 1 and 2. The strokes of the bars 1 and 2 are limited at the outer side of the frame by means of stop members 5. To the thread guide bar 1 a stop arm 6 is secured and to the thread guide bar 2 a stop arm 7.

55 To a shaft 8 a pinion 9 is keyed which is rigidly connected with ratchet wheels 10 and 10', the diameters of which are larger than that of the pinion. The teeth of the wheels 10 and 10' are cut in opposite directions. The pinion 9 is in mesh with racks 11 and 12 which are guided in suitable bearings 13. The rack 11 is provided at its ends with stop arms 14 and 15, and in a similar way the rack 12 carries stop arms 16 and 17. To the rack 12 a tension spring 18 is attached. In suitable guides 19 a push rod 20 is slidably mounted which carries at its upper end a shift pawl 22 which is adapted to engage in the teeth of the ratchet wheel 10' and normally bears on a pin 21. At its lower end the push rod 20 is provided laterally with a pivot bolt 23 on which a sleeve 24 has a slidable support. To the said sleeve the lower end of a rocking lever 26 is attached which has a rocking support on a bracket 25, and which is connected with a link 27.

60 Below the push rod 20 a shaft 28 is mounted in suitable bearings, which carries a cam 29. On a pivot bolt 30 a locking pawl 31 is supported which engages in the teeth of the ratchet wheel 10'. On a pivot bolt 32 a pawl 33 is mounted which engages in the teeth of the ratchet wheel 10, and is provided with an arm 34 connected by a link 35 with the push rod 20.

65 For explaining the operation of the mechanism it may be assumed that a heel portion is to be knitted which is to be gradually reinforced from the points A or A' to the points B or B', whereupon the reinforced portion is uniformly continued to the points C and C' respectively, and is gradually reduced to the points D and D'.

70 When starting the manufacture of the goods the locking pawl 31 acting on the ratchet wheel 10 is thrown into inoperative

position, so that the racks 11 and 12 are shifted by the spring 18 into initial positions, and the stop 14 is in its extreme position at the right, and the stop 16 in its extreme position at the left. The shaft 28 and the cam 29 mounted thereon are constantly rotated in the direction of the arrow shown in Fig. 2. The link 27 is controlled by a counting mechanism such as a 10 jacquard pattern, narrowing chain, or the like. When pulling the same to the right and in the direction of the arrow the lever 26 shifts the sleeve 24 into the path of the cam 29. Thereby the push rod 20 is shifted upward, so that the pawl 22 advances the ratchet wheel 10 and the gear wheel 9 connected therewith, so that the racks 11 and 12, are shifted. As the spring 18 has the tendency to pull the rack 12 to the left the locking pawl 31 is provided by means of which the return movement of the ratchet wheels 10 and 10' is prevented. Normally the forward movement of the ratchet wheel 10 is prevented by means of the pawl 33. 25 When the push rod 20 is shifted upward the pawl 33 is thrown out of locking position by means of the rod 35 connected with the arm 34 of the said pawl, so that the ratchet wheel is now free to be moved by the pawl 22. Upon the return movement of the push rod 20 the pawl 33 falls again into engagement with the ratchet wheel. Upon each forward movement of the ratchet wheel 10 the rack 11 is shifted to the left and the 30 rack 12 to the right, so that the distance of the stops 14 and 16 is reduced. Thereby the strokes of the thread guide bars are increased accordingly, because the stops 6 and 7 get into engagement with the stops 14 and 16 later, and the thread guides 3 and 4 can be approached to each other more and more. Thereby the reinforced portion A—B or A'—B' can be made the border lines of which are directed angularly inward, see 35 Fig. 1. As the ratchet wheel 10 is further advanced in the manner just described, the racks 11 and 12 are shifted from the position shown in Fig. 3 into the position shown in Fig. 4, in which the right hand stop 14 of the rack 11 is in the position corresponding to the right-hand stop 17 of the rack 12, and the left hand stop 16 of the rack 11 is in a position corresponding to the left hand stop 15 of the rack 12. The stops 6 and 7 of the thread guide bars 1 and 2 have such breadths, that they are in the paths of both the stops 14 and 17 and 15 and 16 respectively. If the ratchet wheel 10 is further advanced, at the right the stop 17 of the rack 12 is 40 brought into co-operation with the stop 6 of the thread guide bar 1, and at the left the stop 15 of the rack 11 is brought into co-operation with the stop 7 of the thread guide bar 2 (Fig. 4). Thereafter the stops 15 and 17 are moved farther outward, so that the

movement of the thread guides 1 and 2 is shortened at the inner end, and the reinforced portion C—D or C'—D' is produced the border line of which is directed angularly outward (Fig. 1).

It will readily be understood, that the position of the points B and B', that is the inner limit of the reinforced portion depends on the distance of the stops 14 and 15, and 70 16 and 17 respectively. By setting the stops in different positions the relative position of the points B and B' can be changed. In any case it is necessary first to obtain the breadth of the reinforced portion which can be attained with the racks 11 and 12, before 75 80 the breadth of the reinforced portion can be reduced again.

In the example shown in Fig. 1 the breadth of the reinforced portion remains the same on the parts bordered by the lines B—C and B'—C', for which purpose the ratchet wheel 10 is not shifted when knitting these portions. Of course, such parts with parallel border lines can also be made at any parts of the lines A—B and C—D, or 85 A'—B' and C'—D', for which purpose the counting mechanism by means of which the roller 24 is brought into the path of the cam 29 is thrown out of action. But also in these cases the portions with inclined and straight border lines must at first be continued to the innermost points B, B', before 90 95 the return movement is possible.

I claim herein as my invention:

1. In a hosiery frame, the combination 100 with a pair of thread guides having reciprocating movements in opposite directions, of a pair of stop members each adapted to arrest either one of said thread guides and formed on adjacent sides with rack teeth, a pinion between said stop members and engaging in the teeth thereof, and means operative while the frame is in operation to impose rotary movement to said pinion.

2. In a hosiery frame, the combination 110 with a pair of thread guides having reciprocating movements in opposite directions, of a pair of parallel rods each having stops at both ends and formed on adjacent sides with rack teeth, the stops located at opposite sides 115 of the rack being arranged for arresting engagement with one of the thread guides, a pinion engaging said rack teeth and adapted to shift the rods in opposite directions, and means operative while the frame is in operation to rotate said pinion.

3. In a hosiery frame, the combination 120 with a pair of thread guides having reciprocating movements in opposite directions, of a pair of parallel rods each having stops ad- 125 justably mounted at both ends and formed on adjacent sides with rack teeth, the stops located at opposite sides of the racks being arranged for arresting engagement with one of the thread guides, a pinion engaging said 130

rack teeth and adapted to shift the rods in opposite directions, and means operative while the frame is in operation to rotate said pinion.

5. In a hosiery frame, the combination with a pair of thread guides having reciprocating movements in opposite directions, of a pair of parallel rods each having stops at both ends and formed on adjacent sides with 10 rack teeth, the stops located at opposite ends of the racks being arranged for arresting engagement with one of the thread guides; a pinion engaging said rack teeth and adapted to shift the rods in opposite directions, and 15 means operative while the frame is in operation to rotate said pinion, said means com-

prising a pawl and ratchet mechanism, a rotary cam, and means to throw said pawl and ratchet mechanism and cam into position for coöperation with each other.

6. In a knitting frame, at least one thread guide in addition to the main knitting mechanism, a pair of parallel racks, stops arranged on said racks for stopping the thread guide and controlling its stroke, a pinion engaging said racks for movement in opposite directions, and selectively controlled operating means for the pinion.

In testimony that I claim the foregoing as my invention, I have signed my name.

FRANZ CECKA.
